Design for Daguerreotype Cases —

Patented Feb. 27, 1855 —

Drawing as corrected by me
Feb. 10 1855

Henry A. Eckmeyer

Des. 694

Henry A. Eickmeyer, of Philadelphia, Pa.
Letters Patent No. 694. Dated Feb. 27, 1855.

The schedule referred to in these Letters Patent, and making part of the same.

To all whom it may concern:

Be it known that I, Henry A. Eickmeyer, of the city of Philadelphia and State of Pennsylvania, have invented or produced a new and original design for daguerreotype cases, and I do hereby declare that the following is an exact description of the same.

The nature of my improvement consists in the formation of a case substantially as is exhibited in the drawings accompanying this specification and making a part of the same, that is, by rounding the two edges on which the hinges and clasp are respectively placed, and by embossing or otherwise raising the cover and under side of the case, give the appearance of a band or bands surrounding the case.

What I claim as my invention, and desire to secure by Letters Patent, is

The construction of a case for daguerreotype or other purpose, rounded on the front and back edges, and banded, as described in the above specification, and set forth in the drawings accompanying this application.
